TRAIN-CONTROLLING SYSTEM.

1,342,572.

Specification of Letters Patent. Patented June 8, 1920.

Application filed May 23, 1917. Serial No. 171,469.

To all whom it may concern:

Be it known that we, BENJAMIN A. PRINCE and ELDRIDGE I. LA COUNT, citizens of the United States, and residents of Worcester, in the county of Worcester and State of Massachusetts, have invented a new and useful Improvement in Train-Controlling Systems, of which the following is a specification.

Our invention relates to systems for preventing railroad accidents, such as collisions, derailments, running on to open switches, etc., by means of electrical apparatus and circuits carried by the train and arranged to coöperate through ramps or contact plates located in the block-section in which the train is running with apparatus and circuits connected to and associated with the next block ahead.

The general object of our invention is to provide means whereby a train may automatically be brought to a stand-still in a given block when the next block ahead has been rendered "unsafe" from any cause, such for example as a broken rail, an open switch, or the presence of another train therein; to stop the train in a given block when any road bed circuit of the block ahead is opened or the road bed apparatus of such block short-circuited or otherwise disorganized; and to stop the train whenever any train circuit is opened or the train apparatus short-circuited or rendered incapable of performing its intended function.

A particular object of our invention is to provide means whereby a normally energized electro-magnet carried by the train and hereinafter referred to as the "train-stopping" magnet is deenergized when the block in advance of that in which the train is running has been rendered unsafe or when any train or road bed circuit or apparatus is for any reason rendered inoperative, and by such de-energization causes the application of the air-brakes.

To these and other ends tending to improve and simplify systems of this general type and increase the efficiency of the same, our invention comprises an air-brake valve normally closed by an electro-magnet which

is normally energized directly by a source 50 carried by the train and the circuit of which may be momentarily broken at a given point in every block and then instantly closed by being looped into one of the road-bed circuits connected to the block ahead, so that 55 the circuit of said magnet will be opened if said block has been rendered unsafe, the magnet deenergized and the air-brake valve opened to apply the brakes.

By means of the aforesaid magnet directly 60 energized by the source without the intermediary of a relay or commutator actuated by a control magnet, all danger of faulty operation due to the sticking of such relay or the armature of the control magnet is 65 overcome and the operation of the system is rendered certain and positive. The air-brake valve which is held on its seat by the normally energized magnet is forced from such seat, when said magnet is deenergized, 70 by air compressed to about seventy pounds per square inch, and thereby all danger from failure of operation due to sticking of the armature of said magnet is avoided.

Our invention also comprises an electro-magnetically controlled switch at the end of every block whereby the circuit formed by looping the circuit of the train-stopping magnet into a road-bed circuit may be opened or closed according to the condition 80 of the next block ahead of that in which the train is running, and the position of the armature of said train-stopping magnet correspondingly modified.

Various other features of novelty will 85 hereinafter be described and particularly set forth in the appended claims.

The drawings which accompany and form a part of this specification diagrammatically represent the preferred embodiment of our 90 invention; but it will be understood that both the apparatus and the circuit arrangements therein conventionally shown may be materially modified by those skilled in the art without departing from the invention as 95 defined by the appended claims.

In the drawings—

Figure 1 shows an automatic electrically-

actuated train-controlling system embodying our invention, the several moving parts of the train and track-apparatus being represented in the positions which they occupy before the train-circuits are in coöperation with the road-bed circuits. Fig. 2 is a diagram showing the position of the track-magnet and the switch carried thereby during the coöperation of the train and road-bed circuits when the block ahead of the train is safe. Fig. 3 shows the position assumed by said moving parts when the block ahead of the train has been made unsafe by being short-circuited by another train or metallic obstruction, or by the breaking of the continuous rail or one of the members of the sectional rail. Fig. 4 is a plan view of the register which is arranged for actuation by the train-stopping magnet.

Each of the figures represents a block section consisting of a rail 1, the joints of which are bonded to insure electrical continuity and a rail 2, the component parts of which are also electrically bonded, but the sections of which are insulated from the contiguous sections 2', 2'', the electrically continuous portion of each section 2, 2', 2'', etc., being co-extensive with the length of the block section. The rails 1 and 2 will hereafter be referred to as the "continuous rail" and the "sectional rail" respectively. Located between the ends of each sectional rail and preferably at a point some distance from the forward end of the same is a ramp or contact plate or rail 3 arranged parallel to the rails 1 and 2 and adjacent to one or the other so that a shoe carried by the train may make electrical contact with the same. For convenience of illustration the ramp 3 is shown at the end of section 2' and adjacent to the outer side of rail 1, but it will be understood of course that said ramp may be placed adjacent to the outer side of the rail 2' or may be located between the rails. The ramp 3 by means of a conductor, which may include the resistance 4, the sectional rail 2 and the conductor 5 is connected to one terminal of the track-magnet 6, the other terminal of which is connected to the continuous rail by the conductor 7.

Arranged parallel to the ramp 3 is a somewhat shorter ramp 8 so arranged that its coöperating shoe does not strike the same until after the other shoe has made contact with ramp 3 and having its forward end in the rear of that of ramp 3 so that its shoe will leave the same before the other shoe breaks contact with ramp 3. By means of a conductor 9 preferably carried by the telegraph poles beside the track the ramp 8 is connected by way of the track-switch hereinafter described to the continuous rail.

To the plunger 10 of the magnet 6 which may be of any suitable construction and

which preferably is of the hollow core solenoid type shown in the patent to Orcutt, No. 1,114,642 dated October 20, 1914 is secured an armature 11 movable between the lower end of the sheath 12 which incloses the magnet and the back stop 13.

The plunger carries a switch herein shown as an insulating cylinder 14 having a conducting ring 15 with which the brushes 16, 16' are arranged to make contact when the magnet is energized, said switch normally being held in its lowermost position shown in Fig. 1 by the spring 17. Between the brush 16' of said switch, hereinafter referred to as the "track-switch," and the conductor 7 is a resistance 18, so that the track-switch ramp 8 by means of conductors 9 and 7 is connected through said resistance to the continuous rail when the magnet 6 is energized and is disconnected therefrom when the latter is deenergized.

At the end of block 2, ramps 3', 8' are represented, the former being connected through resistance 4' to the sectional rail 2' and the latter being connected by the wire 9' to apparatus identical with that to which the conductor 9 is connected, it being understood of course that every block is provided with a pair of ramps such as 3, 8, connected to the next block ahead and to apparatus associated with the far end of such block identical with that shown in Fig. 1.

The track switch and its magnet are located preferably on a telegraph pole beside the track.

For convenience of identification the ramp 3 will be hereinafter referred to as the "track-magnet ramp" and the ramp 8 as the "track-switch ramp." Carried by the train and preferably by the pony truck of the locomotive is a contact shoe 19 of any suitable construction and herein shown as a downwardly curved member of spring material fixed at one end and forced by the elasticity of the metal of which it is formed against the stop 20 at the other, the curved portion of said shoe being arranged to come into direct contact with and ride up upon the ramp 3 and be held in firm electrical contact therewith by virtue of such elasticity. The shoe 19 hereinafter designated as the "track-magnet ramp-shoe" is connected by wire 21 to the brush 22 of the generator 23 carried by the train. The other brush 24 is connected to the continuous rail 1 by the conductor 25 and the contact member 26 which as shown may be one of the locomotive wheels.

The shoe 27 similar in construction to shoe 19 and hereinafter referred to as the "track-switch ramp-shoe" is also fixed to the train and preferably to the pony truck of the engine and arranged to make contact with the track-switch ramp. The free end of the

shoe 27 is forced by its elasticity against the lower face of the stop 28 which is connected by the resistance 29 and the conductor 25 to the brush 24 of the generator. The resistance 29 is substantially equivalent to resistance 18 so that when the shoe 27 is in engagement with the ramp 8 and the resistance 29 thereby cut out of the circuit formed by the coöperation of said shoe and ramp and by the coöperation of contact member 26 and continuous rail, the resistance 18 by its substitution will be effective in preventing any material change in the current intensity of said circuit. The upper face of said stop 28 is of insulating material, as shown, so that in case the end of the shoe 27 is forced against said upper face, the resistance 29 will still remain out of circuit. The fixed end of the shoe 27 is connected by wire 30 to the brake-controlling or train-stopping magnet 31 and the other terminal of the latter is joined to the brush 22 of the generator, so that normally there is a closed circuit through the resistance 29 and the train-stopping magnet, the resulting normal energization with the latter maintaining the valve 32 on its seat 33, in the particular example shown in the drawings. It will be understood however that said train-stopping magnet may be operatively associated with the engine throttle or any other instrumentality whereby the train may be stopped or controlled. In the particular apparatus shown said valve 33 is secured to the plunger 10 of the magnet 31 and is arranged to rest, when said magnet is energized, upon its seat in the casing 34 which is mounted upon the back yoke 35 of said magnet and thereby close the port 36 which otherwise would be open to the atmosphere by the passage 36'. The casing 37 of the blanking valve (not shown) is mounted upon the valve casing 34 and insulated therefrom by the bushing 38. The casing 37 is provided with a passageway 39 which will be put into communication with the atmosphere when the valve 32 is off its seat and thereby effect the application of the air-brakes in the manner described in Patent No. 1,114,642 and the improvement thereon disclosed in the application of Eldridge I. La Count, Serial No. 125,112 filed October 11, 1916.

Arranged to be actuated by the plunger 10 of the magnet 31 and preferably as shown directly attached to the armature 11 thereof is a commutator comprising two insulated portions 40, 40' and a conducting portion 41. The brush 42 is arranged to be in contact with the conducting portion 40 of the commutator irrespective of the position of the armature 11 and is connected to the brush 24 of the generator.

A safety-signal indicating device herein shown as a lamp 43 is connected by the wire

44 to the brush 45 arranged to make contact 65 with the conducting member 41 only when the magnet 31 is energized. The brush 46 is arranged to be in contact with the insulation member 40' when the train-stopping magnet is energized and to make contact 70 with the conducting member 41 when said magnet is deenergized, as shown in Fig. 3. By the conductor 47 the last mentioned brush is connected to the danger-signal indicating device herein shown as the lamp 75 48, and both indicating devices are connected to the brush 22 of the dynamo by the conductor 49.

It will be obvious that when the parts are in the position shown in Fig. 1 there will 80 be a circuit through the lamp 43 and the generator, and that the circuit of the lamp 48 will be open at the commutator, while in the position shown in Fig. 3 there will be a circuit through the generator and the 85 danger-signal indicating lamp, and the circuit of the safety-signal indicating lamp will be broken at the commutator. We have found that the difficulties heretofore experienced with switches and circuit-changing devices of the spring-controlled pivoted-armature relay type are completely eliminated by the use of an electro-magnet of the solenoid type, the plunger of which carries one element of a circuit-controlling 90 device. By means of such arrangement the system is greatly simplified and rendered certain and reliable in operation, while in the case of the train-carried portion of the system the vibration of the train has no 100 injurious effect on the circuit changer or commutator because of the entire absence of the spring-retracted members heretofore employed.

The operation of the system above described is as follows: Before the shoes have made contact with their respective ramps the circuit of the track-magnet 6 is open, this circuit being hereinafter termed the "track-magnet circuit" viz., the circuit 3, 4, 105 2, 5, 6, 7, 1, 26, 25, 23, 21, 19 and said magnet consequently is deenergized, and its armature 11 is forced down on the back stop 13 by the spring 17 so that the brushes 16, 16' are out of contact with the ring 15 as 110 shown in Fig. 1. The circuit of the train-stopping magnet 31 is closed through the generator, this circuit being hereinafter termed the "train-stopping-magnet circuit," viz., the circuit 22, 31, 30, 27, 28, 29, 25, 24, 120 125 and the armature of said magnet is against the sheath 12 so that the brushes 42, 45 close the circuit of the safety-signal indicating device 43 through the conducting member 41 of the train-controlling-magnet commutator. The circuit hereinafter termed the "track-switch circuit," viz., the circuit 8, 9, 16, 16', 18, 7, 1, 26, 25, 23, 31, 27, is open at

two places, viz., between the shoe 27 and ramp 8, and the brushes 16, 16', and the ring 15. The circuit of the danger-signal device 48 is open at the train-controlling-magnet commutator.

As soon as the shoe 19 is brought in contact with the track-magnet ramp 3, the track-magnet circuit is closed, the armature of the track-magnet is drawn up to its front stop 12 and the ring 15 is placed in contact with the brushes 16, 16', thereby closing one of the breaks in the track-switch circuit. Shortly afterward the shoe 27 makes contact with the track-switch ramp 8 and thereby closes the other break in the track-switch circuit, by looping the train-controlling-magnet circuit into the track switch circuit, the resistance 29 being cut out of said circuit and replaced by the equivalent resistance 18, so that there will be no change in the degree of energization of the train-controlling magnet 31. The track-switch circuit may now be traced as follows; viz., from the generator 23 through magnet 31 to shoe 27, ramp 8, conductor 9, brush 16, conducting ring 15, brush 16', resistance 18, conductor 7, continuous rail 1, contact maker 26, and thence by the conductor 25 back to the generator. The momentary opening of the train-controlling-magnet circuit which occurs when the shoe 27 rides up over the ramp 8 and thereby breaks contact with its back stop 28, will not suffice to deenergize the train-stopping magnet for practically simultaneously with such opening, said circuit is closed in the manner above indicated and the armature of said magnet and its associated apparatus maintain their normal positions, the lamp 43 remaining lighted and the circuit of the lamp 48 remaining open.

However, when the block ahead of that in which the train is running has been rendered unsafe, the track-magnet will remain deenergized, and the resulting changes in the positions of the moving members are shown in Fig. 3.

Breaks in the tracks are indicated at X and Y, and Z represents a metallic obstruction such as the truck of a train short-circuiting the terminals of the track-magnet. As will be obvious in either case the magnet 6 will remain deenergized, and the track-switch circuit will be open at the switch so that when the shoe 27 rides up over the ramp 8 the circuit of the train-stopping magnet will be opened, the magnet deenergized and its armature will take the position shown in Fig. 3, said armature dropping to its back stop 18' by gravity assisted by the pressure of the air in the passage 39 acting against the valve 32, so that it will be impossible for the apparatus to fail on account of any possible sticking of the armature 11 to the sheath 12. It

will be obvious that the result above set forth, viz., the opening of the circuit of the train-controlling magnet, will also be effected by the rupture of conductors 5, 7 and 9, or any of them, irrespective of the condition of the track. It will also be obvious that the short-circuiting of the train apparatus or the breaking of the circuits thereof will have the effect of opening the circuit on the magnet 31 and thereby stopping the train.

The track-magnet ramp 3 may be about sixty feet in length and its coöperating shoe should strike the same long enough before shoe 27 makes contact with ramp 8 to permit the energization of the track-magnet and the setting of the track-switch to the position shown in Fig. 2. Obviously the shoe 27 must break contact with its ramp before the track-magnet circuit has been opened by the breaking of the contact between the shoe 19 and ramp 3.

As more fully described in the application of Eldridge I. La Count, Serial No. 125,112 above referred to, the brakes will remain set after the train has been stopped by the system herein described until the valve 32 is again brought to its seat which may be effected by the operation of an adjunct to the engineer's valve under certain conditions not necessary to set forth herein. It being desirable to register the instances of operation of said adjunct, we provide means for showing indirectly the number of times said adjunct is operated during a run. The particular means shown comprise a register actuated by the armature of the magnet 31. In the present instance the lever 50 provided with an offset 51 at one end is pivoted at 52 to a support 53 and has a pawl 54 pivotally connected to its other end, said pawl being connected by the spiral spring 55 to the pivot 52. The ratchet wheel 56 of a register 57 which in the present instance has three dials on which the hands 58, 58', 58'' register units, tens and hundreds respectively, is actuated by the pawl 54 every time the end of the commutator strikes the offset 51 of the pivoted lever.

Inasmuch as the train after having been brought to a standstill by our system cannot again be started unless the engineer operates the adjunct above referred to, it follows that the register above described will make a record of the operations of said adjunct. It will be understood however that the particular form of register constitutes no part of our invention and that any suitable means arranged for operation by the armature or plunger of the train-stopping magnet may be employed to record the number of times the train is automatically stopped and consequently the number of times it is started again by the

operation of the adjunct to the engineer's valve.

Having thus particularly described an illustrative embodiment of our invention 5 without, however, limiting the same there-to what we claim as new and desire to secure by Letters Patent is:

1. In a train controlling system, the combination with an electrically-continuous rail 10 and a sectional rail, each section of which is electrically-continuous but insulated from its contiguous sections, of a source of electrical energy carried by the train, a train-stopping magnet normally energized directly by said source, a safety-signal indicating device, a danger-signal indicating device, a commutator actuated by said train-stopping magnet, a connection from said source to the conducting member of said 15 commutator, a connection from said safety-signal indicating device to said conducting member when said train-stopping magnet is energized, and a connection from said danger-signal indicating device to the insulation member of said commutator when said train-stopping magnet is energized.

2. In a train controlling system, the combination with an electrically-continuous rail and a sectional rail, each section of which is 20 electrically-continuous but insulated from its contiguous sections, of a source of electrical energy carried by the train, a train-stopping magnet normally energized directly by said source, a safety-signal indicating device, a danger-signal indicating device, a commutator actuated by said train-stopping magnet, means connecting the conducting member of said commutator to said source, means connecting said safety-signal 25 indicating device to the conducting member of said commutator only when said train-stopping magnet is energized, and means connecting said danger-signal indicating device to the conducting member of said commutator only when said train-stopping magnet is deenergized.

3. In a train controlling system, the combination with an electrically-continuous rail and a sectional rail, each section of which is 30 electrically-continuous but insulated from its contiguous sections, of a source of electrical energy carried by the train, a train-stopping magnet normally energized directly by said source, a normally-open track-circuit formed in part by said sectional and continuous rails, a ramp on the road-bed, a shoe carried by the train and arranged to cooperate with said ramp to close said track-circuit through said source of electrical energy, an electro-magnetically operated track switch controlled by said track circuit, said track-switch having a single conducting member and an insulating member, a second track circuit, brushes connected to the terminals of said second track circuit and nor-

mally in contact with said insulating member, a second ramp on the road-bed, and a shoe carried by the train and arranged to co-operate with the last mentioned ramp to close the circuit of said train-stopping magnet through said conducting member of said track switch.

4. In a train controlling system, the combination with an electrically-continuous rail and a sectional rail, each section of which is 45 electrically-continuous but insulated from its contiguous sections, of a source of electrical energy carried by the train, a train-stopping magnet normally energized directly by said source, a normally-open track-circuit formed in part by said sectional and continuous rails, a ramp on the road-bed, a shoe carried by the train and arranged to co-operate with said ramp to close said track-circuit through said source of electrical energy, a solenoid in 50 said track circuit, a switch carried by the plunger of said solenoid and having a single conducting member and an insulating member, a second ramp on the road-bed, and a shoe carried by the train and arranged to co-operate with the last mentioned ramp to close the circuit of said train-stopping magnet through said conducting member of said track switch.

5. In a train controlling system, the combination with an electrically-continuous rail and a sectional rail, each section of which is 55 electrically continuous but insulated from its contiguous sections, of a source of electrical energy carried by the train, a solenoid energized directly by said source, a casing mounted on the yoke of said solenoid and provided with a single valve seat communicating with a single passageway containing air under pressure, a valve carried by the plunger of said solenoid, said valve being arranged to rest on said seat when said solenoid is energized and thereby close said passageway, and means in the section ahead of that in which the train is running for directly controlling the action of said solenoid, whereby upon the deenergization of the latter said valve will be forced from its seat by the action of gravity and the pressure of the air in said passageway and will open said 60 passageway directly to the atmosphere.

6. In a train-controlling system, a train-stopping magnet, a danger-signal indicating device and a safety-signal indicating device; the circuits of both of said devices being associated with that of said train-stopping magnet, a commutator actuated by said train-stopping magnet, said commutator having a conducting member and an insulation member, three brushes, one arranged to 65 be always in contact with said conducting member and the other two being so arranged that one is in contact with said conducting member when the other is in contact with said insulation member, and connections 70

from the last mentioned brushes to said indicating devices respectively.

7. In a train controlling system, a track-solenoid arranged to be energized by a source of electrical energy carried by the train, a track-switch carried by the plunger of said track solenoid, a circuit associated with said track-switch, and two brushes connected respectively to the terminals of said circuit, said switch being provided with a

single conducting member and an insulation member and said brushes being arranged so as to make contact with said conducting member only when said track solenoid is energized.

In testimony whereof, we have hereunto subscribed our names this 22nd day of May, 1917.

BENJAMIN A. PRINCE.
ELDRIDGE I. LA COUNT.
